Hilts

UNITED STATES PATENT OFFICE.

JOHN SANFORD SMALL, OF ELKHART, INDIANA.

FILE.

Application filed December 23, 1926. Serial No. 156,589.

This invention relates to a card file of the overlapping type, having novel means providing for offsetting the cards laterally with relation to one another.

5 The invention will be best understood by reference to the following description, when taken in connection with the accompanying drawings of one specific embodiment thereof, while its scope will be more particularly 10 pointed out in the appended claims.

In the drawings:

Fig. 1 is a front elevation of a file exemplifying the invention;

15 Fig. 2 is a sectional view on line 2—2 of Fig. 1;

Fig. 3 is a sectional view of one card and its carrier on line 3—3 of Fig. 1;

20 Fig. 4 is a sectional view similar to Fig. 3, but with the carrier bent, illustrating the mode of detaching the card from its carrier;

Fig. 5 is a sectional view, on an enlarged scale, of a portion of one of the carriers on line 5—5 of Fig. 2;

25 Fig. 6 is a sectional view, on an enlarged scale, of the carrier on line 6—6 of Fig. 2; and

Fig. 7 is a sectional view on line 7—7 of Fig. 6.

Referring to the drawings, and to the embodiment of the invention which is selected for exemplification, there is shown a card file comprising a series of overlapping cards 8, each carried by a carrier, herein comprising a bar 9 of resilient material such as 30 tempered steel, said bars being arranged edge to edge, and having their terminal portions received by guides 10 presented by an appropriate support, herein a panel or tray 11. Removal of the carriers from their 35 guides is conveniently effected by bending each carrier to enable the distance between its ends to be reduced. In the present example, each of the guides 10 is presented by a metallic strip 12, suitably secured as by 40 spot-welding to the panel 11. To maintain the carriers elevated above the panel, thereby to facilitate their being sprung to enable 45 any individual carrier to be grasped for removal, the strip 12 presents a raised bead 13 (see Fig. 2).

50 Each carrier presents two prongs 14, directed outwardly toward the ends of the carrier, which prongs in the present example are conveniently formed as integral parts of metallic members 15, best shown in Figs. 6 and 7, which are appropriately secured to

the bar 9 by the provision of arms 16 clasped about the bar, and received in notches 17 presented by the edges of the bar. Before the member is attached to the bar, it has a 60 U-shaped formation. Its arms are inserted in the notches in the bar, and the arms are then clinched over on the rear face of the bar, as shown in Fig. 6, thereby securely attaching the member to the bar. The prong 14 is conveniently formed by punching the member to form the tongue, which is forced in an outward direction (see Fig. 7).

Each card presents a plurality of pairs of perforations, herein two pairs 18, 18, and 18', (see Fig. 3), the perforations of either pair being adapted to receive the prongs 14, the arrangement being such that the prongs can be removed from one pair and inserted in the perforations of another pair, thereby to cause a lateral offsetting or displacement of the card with reference to one or more of the others. In Fig. 1, two of the cards are shown offset laterally to the right of the others. This offsetting can be utilized for 70 a variety of purposes, which require no description, as the principle of offsetting is well known to those skilled in the art.

Each of the outwardly directed prongs 80 overlies the margin of the perforation in which it is received, and accidental displacement of the cards lengthwise of their carriers is thereby prevented, inasmuch as the card can be displaced laterally only by first removing the carrier from the panel and then springing the carrier in the manner illustrated in Fig. 4, to enable the prongs to be withdrawn from the perforations in which they are received, and the file can therefore be moved about from place to place, without requiring careful handling, as no amount of jarring or handling of the file can cause the cards to be displaced laterally. The advantage of this is apparent, 85 when it is considered that all of the work of posting might otherwise be undone by 90 accidental displacement of the cards after 95 they have once been arranged.

Having thus described one embodiment 100 of the invention, but without limiting myself thereto, what I claim and desire by Letters Patent to secure is:

1. In a file, the combination of a series of 105 overlapping cards, a support, and means connecting said cards to said support and maintaining them in overlapping relationship, said means having provision for per-

mitting said cards to be offset laterally with relation to one another and for preventing such offsetting from taking place without first disengaging and removing said cards 5 from said connecting means.

2. In a file, the combination of a series of overlapping cards, a support, and means connecting said cards to said support and maintaining them in overlapping relationship, said means having provision for permitting said cards to be offset laterally with relation to one another and for preventing such offsetting from taking place without first detaching said connecting means from 10 said support.

3. In a file, the combination of a series of overlapping cards each presenting a plurality of pairs of perforations, a support presenting guides, and a series of parallel 20 bars arranged edge to edge and having their terminal portions received by said guides, each bar presenting a pair of projections whose free ends are directed outwardly toward the ends of said bar, said projections being respectively received in the perforations of one pair, and being adapted to be re- 25

ceived in the perforations of the other pair, each bar being flexible to enable the distance between its ends to be reduced, thereby to enable the ends of said bar to be detached from said guides and to enable the projections on said bar to be withdrawn from the pair of perforations in which they are located and inserted in the other pair of perforations. 30

4. A filing element comprising, in combination, a card presenting two perforations, a supporting bar, and two metallic prongs rigidly secured to said bar and received in said perforations, respectively, said prongs 40 extending in opposite directions lengthwise of said bar.

5. A filing element comprising, in combination, a card presenting two perforations, a supporting bar, and two metallic members 45 clasped about the body of said bar and presenting prongs received in said perforations, respectively, said prongs extending in opposite directions lengthwise of said bar.

In testimony whereof, I have signed my 50 name to this specification.

JOHN SANFORD SMALL.
